UNITED STATES PATENT OFFICE.

ROBERT HUGH COLLINGHAM, OF RUGBY, ENGLAND, ASSIGNOR TO GENERAL ELECTRIC COMPANY, A CORPORATION OF NEW YORK.

VAPOR GENERATOR.

Application filed May 26, 1925, Serial No. 33,056, and in Great Britain June 26, 1924.

This invention relates to vapor generators or boilers and more particularly to generators or boilers for vaporizing liquid which is contained in one or more revolving tubes. The invention is especially well adapted for use where the liquid to be vaporized is mercury, and in the following specification it is specifically described as being used with mercury. It will be understood, however, that it is not necessarily limited thereto.

When such generators are mounted on a moving platform, for example, when used on board a ship or air vessel, it is necessary to provide means for maintaining the static head of the mercury feed on each of the tubes when the vessel on which the boiler is installed is pitching or rolling, or both. Such movements of the vessel preclude the use of a common feed tank as the heads of mercury on the various tubes would obviously be unequal when the vessel was displaced from the normal level keel, and might result in some of the tubes being burned out owing to their being deprived of their supply of mercury.

The object of the present invention is to provide means for supplying mercury to all the tubes under an equal static head independently, and for a consideration of what I believe to be novel and my invention, attention is directed to the accompanying description and the claims appended thereto.

In the drawing, Fig. 1 is an end elevation of a mercury feeding arrangement embodying my invention; Fig. 2 is a side elevation of the construction shown in Fig. 1, and Fig. 3 is a cross-sectional elevation of a vessel fitted with a mercury feeding arrangement embodying the invention.

Referring to the drawing, Figs. 1 and 2, 5 are the revolving tubes of a mercury boiler of the revolving tube type, this being a now known type of boiler. 6 indicates a mercury turbine which is supplied with mercury vapor by means of a boiler comprising the revolving tubes 5. The last stage wheel of the turbine is indicated at 7 and the vapors discharged from it impinge against the cooling tubes 8 of a mercury condenser. The mercury vapors discharged against the tubes 8 are condensed by them, and after being condensed, the liquid mercury drops down into a sump 9 formed at the lower portion of the condenser casing. In sump 9 are baffles 10 and 11 which extend at a right

angle to each other and are provided with numerous openings 12 for the passage of the mercury. The purpose of these baffles is to deaden the surging action of the mercury when the ship is rolling and pitching. 60 Below sump 9 is a feed chamber 13 divided into compartments 14 by suitable partition plates 15, there being as many compartments 14 as there are revolving tubes 5. In partition plates 15 are liquid level equalizing 65 pipes 16 which serve to connect adjacent compartments 14. Also in feed chamber 13 are a number of baffles 16^a which extend at a right angle to partition plates 15. In baffles 16^a are openings 17. These baffles 70 serve in the same manner as do baffles 10 and 11 to prevent surging action of the mercury when the ship is rolling and pitching. Sump 9 forms a liquid supply chamber and is connected to feed chamber 13 by transversely extending pipes 18 and 19 having spaced inlet ends, the pipe 18 (Fig. 1) leading from the right hand side of sump 9 to the left hand side of feed chamber 13, and pipe 19 leading from the left hand side of 75 sump 9 to the right hand side of feed chamber 13. Compartments 14 are each connected by pipes 20 to one of the revolving boiler tubes 5, the upper ends of these pipes terminating well within the feed chamber 13 and 80 preferably just below the level equalizing pipes 16.

With the above described arrangement, the mercury from sump 9 flows through pipes 18 and 19 to the compartments in feed 90 chamber 13, the level in the respective compartments being equalized by reason of the pipe connections 16. From compartments 14 the mercury is fed through pipes 20 to the revolving boiler tubes 5.

Conduit means for conveying mercury vapor from the boiler tubes 5 to the turbine is not shown in the drawing. Any suitable arrangement may be used.

The operation of the invention will be 100 more readily understood from a consideration of Fig. 3 wherein a mercury boiler comprising three revolving tubes 5 is shown, mounted in a ship indicated in outline at 21. The arrangement shown in Fig. 3 is the same 105 as that shown in Figs. 1 and 2, and the same reference numerals are applied to corresponding parts. It will be noted that with this arrangement, although the ship is tilted toward the right, nevertheless the mercury 110

liquid will continue to be fed from sump 9 to feed chamber 13 by reason of the particular arrangement of the feed tubes 18 and 19. It will also be clear that either tube 18 or tube 19 will always be in a position to feed mercury from sump 9 to chamber 13.

With the vessel 21 tilted as shown, the level of the liquid in the compartments 14 of feed chamber 13 will each assume levels 10 as indicated by the lines 22. In each instance, however, the head of mercury on the tube 20 will remain the same, such heads being represented by the characters h_1 , h_2 and h_3 , which, in each instance, it will be seen, 15 are equal.

In connection with the tubes 16, it is their function to at all times maintain the level of the liquid in the respective compartments 14 at the same height and they will serve 20 to perform this function by reason of the fact that they are of a length such as to extend from approximately the center of one compartment to the center of the other.

In accordance with the provisions of the 25 patent statutes, I have described the principle of operation of my invention, together with the apparatus which I now consider to represent the best embodiment thereof, but I desire to have it understood that the apparatus shown is only illustrative and that the invention may be carried out by other 30 means.

What I claim as new and desire to secure by Letters Patent of the United States, is:

35 1. In combination, a boiler comprising a plurality of boiler tubes, a liquid chamber located above said tubes, means providing a plurality of compartments in said chamber, means for supplying liquid to said compartments, said means including a liquid supply 40

chamber and conduits having spaced inlet ends connected with said supply chamber, said inlet ends being spaced apart in a horizontal direction, and conduits connecting said compartments to said tubes.

45 2. In combination, a boiler comprising a plurality of boiler tubes, a liquid chamber located above said tubes, means providing a plurality of compartments in said chamber, means including supply pipes having horizontally spaced inlet ends for supplying liquid to said compartments, conduits connecting said compartments to said tubes, and means for equalizing the liquid levels in said compartments.

50 3. In combination, a boiler comprising a plurality of boiler tubes, means providing a plurality of liquid compartments located above the tubes, conduits connecting said compartments to said tubes, a source of liquid supply, and means for conveying liquid therefrom to said compartments, said means comprising a liquid supply chamber and transversely extending pipes having horizontally spaced inlet ends connected 55 with said supply chamber.

5. In combination, a boiler comprising a plurality of tubes, a liquid feed chamber located above the tubes, said chamber being provided with a plurality of compartments, 70 conduits connecting said compartments to said tubes, means for equalizing the liquid levels in said compartments, a liquid supply chamber located above the liquid feed chamber, and feed pipes which extend from each 75 side of the liquid supply chamber to the opposite side of the liquid feed chamber.

In witness whereof, I have hereunto set my hand this 11th day of May 1925.

ROBERT HUGH COLLINGHAM.
